DOLL AND MEANS FOR CHANGING THE FEATURES THEREOF

Peter R. Aube, Mineola, N.Y.

Application August 2, 1946, Serial No. 687,881

2 Claims. (Cl. 46—135)

1

This invention relates to dolls of that type capable of changes in its facial expression. The object of the present invention is primarily to provide a mechanism of most simple construction for effecting a variety of expressions of the face of the doll.

The mechanism for altering the facial expression of the doll, at the will of the operator, is in accordance with my invention, composed of a minimum number of parts and at the same time is easy and positive in its operation.

The invention, together with the stated and other objects, as will appear as the description proceeds, will be best understood from the following detailed description read in reference to the accompanying drawings in which are illustrated what are presently considered preferred embodiments of the invention and wherein:

Figure 1 is a vertical sectional view through the head of a doll embodying the features of the present invention, certain parts being shown in elevation;

Figure 2 is a vertical sectional view taken substantially on line 2—2 of Figure 1;

Figure 3 is a fragmentary horizontal detail sectional view taken substantially on the line 3—3 of Figure 1;

Figure 4 is a fragmentary horizontal sectional view taken substantially on line 4—4 of Figure 2.

The illustrated embodiment of the invention comprises a hollow skull 11 formed of any suitable material and simulating the skull of a human being, with the exception that in the front thereof, there is provided in that region where normally the nose, mouth and chin are located, an opening 12.

For substantially the entire front or forward half thereof, the hollow head 11 is provided with a central recess 13. Fitted over this mentioned half of the skull 11 is a cover 14 of elastic material; the covering 14 being extended over the opening 12 as shown.

Preferably the covering 14 is of flesh color and is molded or otherwise formed to have the appearance of a countenance, embodying such characteristics of a countenance as eyes (not shown), nose 15, mouth 16, and chin 17.

The covering 14 is so formed as to be easily slipped over the skull and at the edges thereof, the covering 14 is cemented or otherwise positively secured to the skull 11.

The covering 14 in the region of the nose, mouth and chin, and which portion is extended over the opening 12, has a flat area indicated generally at 18. This flat area 18 is substantially

2

of ovate contour and on the inner side of the covering, is rimmed by a continuous bead 19. Bead 19 is provided on the covering 14 preferably by being molded or otherwise being formed integrally therewith. This bead 19 is also provided with a continuous internal groove 20 which accommodates the edge portion of a circular plate or disc 21. The disc 21 may be made of metal or other suitable material and is movable over the areas 18, but its extent of movement being confined, as is apparent, by the bead 19. Because of the shape of the bead 19 and disc 21, movement of the latter will obviously effect a distortion of the elastic covering 14, resulting in varying the facial expression of the doll.

For effecting movement of the disc 21 and thus change the facial expression, there is provided a manually manipulated lever 22. This lever is preferably of the sinuous shape shown to advantage in Figure 1 and adjacent one end thereof is mounted to rock on a shaft 23 that extends transversely of the skull 11 interiorly of the latter. Socket lugs provided internally of the skull 11 and at opposite sides of the skull, accommodate the ends of the shaft or rod 23. The free end of the lever 22 extends through a slot 25 provided in the back of the skull adjacent the neck formation 26 and extends outwardly so as to be readily accessible for manipulation exteriorly of the skull.

Rocking movement of the lever 22 is transmitted to the disc 21 for effecting up and down movements of the latter through the medium of a connecting link 28. Link 28 is pivoted at one end to the inner end of the lever 22 as at 28' and at the opposite end thereof, link 28 is pivoted as at 29 to a bifurcated lug 30 provided on one side of disc 21 as shown to advantage in Figures 1 and 4.

When downward pressure is applied to the free end of lever 22, the latter will rock in a direction to cause the disc 21 to move upwardly within the confines of the bead 19. As the disc moves upwardly, the edges of the same will force the cheek area of the covering 14 upward and outward in the direction of the ears (not shown) causing the edges of the mouth 16 to raise, and the eyes (not shown) to close slightly, thus giving a smiling expression to the face. Movement of the lever 22 in an opposite direction to cause a downward movement of the disc 21 will effect a change in the smiling expression, the degree of downward movement of the disc producing either a normal reposed facial expression or a crying facial expression, as may be desired.

While I have herein described what I believe

to be a preferred embodiment of my invention, nevertheless it is to be understood that various changes may be made therein, within the scope of the claims hereto appended.

What I claim is:

1. A doll head having a face constructed of elastic material provided internally of the head with an integral continuous bead, a lever mounted on an axis disposed transversely of and within the head, a disc having a working fit within the confines of said bead, and a link connection between one end of said lever and said disc for transmitting movement of the lever to the disc and thereby impart a composite movement to the elastic face for varying the facial expression.

2. A doll having a hollow head of which the face is constructed of elastic material having the appearance of a countenance, a member mounted on the inner side of the face material and

movable thereover, means on the inner side of the face material and circumjacent said member for limiting movement of the latter, a lever pivotally mounted within the hollow of said head, and means pivotally connecting the lever with said member for transmitting movement of the lever to said member for varying the facial expression.

PETER R. AUBE.
